Wm. H. Morrison,

Inventor;

William W. Winter

UNITED STATES PATENT OFFICE.

WILLIAM WINTER, OF PHILADELPHIA, PENNSYLVANIA, ASSIGNOR TO HIMSELF, ISAAC TOWNSEND, AND THEODORE H. BEACHER, OF SAME PLACE.

IMPROVED CLAMP FOR CLOTHES-LINES.

Specification forming part of Letters Patent No. 57,263, dated August 14, 1866.

To all whom it may concern:

Be it known that I, WILLIAM WINTER, of the city of Philadelphia, in the State of Pennsylvania, have invented a new and Improved Clamp for Clothes-Lines; and I do hereby declare that the following is a full, clear, and exact description of the construction and operation of the same, reference being had to the accompanying drawings, making a part of this specification, in which—

Figure 1 is a side view of the said improved clamp as applied to use, and Fig. 2 a transverse section across the middle of the same, like letters of reference indicating the same parts when in both figures.

The nature of my said invention consists in making a spring-clamp for a clothes-line so that the middle transverse section of the same will be substantially in the form of a hollow cylinder divided along one of its sides, and with its open ends and sides beveled or rounded off at their inner sides, substantially as hereinafter described and set forth, the same being intended to be strung along in indefinite numbers upon the line for use, as occasion may require.

In the drawings, A is the clamp; B, the clothes-line, and C a piece of fabric secured upon the latter by the former.

The clamp A is intended to be made of horn, metal, wood, or other springy material, and about one and a half inch long, with an inner diameter slightly larger than the diameter of the clothes-line, and of sufficient thickness to give it the requisite strength and springi-

ness to admit of its being slipped with facility over the edges of the fabric upon the line, and thus to secure them together, substantially as represented in Fig. 1. The inner sides of its ends a' a' and separated sides a^2 a^2 are rounded off, as shown in the drawings, so as to render its application, by slipping it longitudinally along over the fabric C on the line B an operation of facility and expedition, an indefinite number of the said clamps A having been previously strung upon the said line.

It will be seen that these clamps applied will be always at hand with the line, and therefore not liable to get lost or mislaid, and being small and light in weight, they will not objectionably interfere with the usual stretching and folding operations. They make very reliable fastenings for the purpose, and afford greater facility in the operations of securing and releasing the clothes.

I wish it to be understood that I do not desire to claim, broadly, the stringing of clothes-clamps upon a line; but,

Having fully described my invention, I claim—

A clothes-line spring-clamp consisting of a hollow cylinder open at each end, divided along one of its sides, and having its inner edges beveled or rounded off, all as set forth and described.

WILLIAM WINTER.
